J. B. MASERANG

RAILWAY TIE AND RAIL FASTENER

Filed Sept. 16, 1924

Attorney

Patented Mar. 24, 1925.

UNITED STATES PATENT OFFICE.

JOHN B. MASERANG, OF BELLEVILLE, ILLINOIS.

RAILWAY TIE AND RAIL FASTENER.

Application filed September 16, 1924. Serial No. 738,049.

To all whom it may concern:

Be it known that I, JOHN B. MASERANG, a citizen of the United States, residing at Belleville, in the county of Saint Clair, State 5 of Illinois, have invented certain new and useful Improvements in Railway Ties and Rail Fasteners; and I do hereby declare the following to be a full, clear, and exact description of the invention, such as will enable others skilled in the art to which it 10 appertains to make and use the same.

This invention relates to new and useful improvements in railway devices, and particularly to ties and rail fastenings.

15 One object of the invention is to provide a hollow metallic tie which is strong and durable to support the rails, and which is adapted to exclude mud and ballast.

Another object is to provide a tie which 20 is so formed that the rail fastener used in connection therewith, is adapted to properly clamp rails of different sizes.

Another object is to provide a novel and improved form of rail fastening which will 25 not become disengaged from the rail or tie.

Other objects and advantages will be apparent from the following description when taken in connection with the accompanying drawing.

30 In the drawing:

Figure 1 is a side elevation of a railway tie, made in accordance with the invention, and showing a rail and the fastening means associated therewith.

35 Figure 2 is a top plan view of the same.

Figure 3 is a vertical transverse sectional view on the line 3—3 of Figure 2, the rail being omitted.

Figure 4 is an enlarged vertical sectional 40 view through the rail fastening means, on the line 4—4 of Figure 2.

Referring particularly to the accompanying drawing, there is shown an elongated hollow metal tie which includes the top and bottom members 10 and 11, and the side members 12, these latter members being secured, at their lower longer edges, to the longer side edges of the bottom member 11, while their upper longer edges are secured 45 to the lower face of the top member 10 inwardly of the longer marginal edges of said top member. This provides that portions 50 of the top member 10 project beyond the side members 12, and in these projecting portions are formed longitudinal series of 55 regularly spaced openings 13, to which ref-

erence will be made later herein. Triangular braces 14 are secured to the outer faces of the side member 12 and to the lower faces of the projecting and apertured portions of the top member 10. A vertical wall 15 extends longitudinally and centrally through the tie, and is secured to the top and bottom members, the ends of said wall having reduced and apertured portions 16 extending 60 beyond the ends of the tie. End walls 17 are disposed at the ends of the tie, and on the lower edges of these plates are lugs 18 which engage in openings 19 formed in the end portions of the bottom wall 11, of the tie. Each end wall is formed with a vertical central slot 20 which receives the reduced portion 16, of the central wall 15, cotter pins 21 being engaged transversely 65 through the openings in said reduced portions 16, whereby to retain the end walls in position. It will be noted that the projecting edge portions of the top wall 10 are slightly thicker than the remainder of said wall, whereby to increase the strength of 70 such portions for the retention of rail fastening devices, which will presently be described.

Disposed transversely of the tie is the rail 75 22, the sides of the base flange of which are arranged to lie in close proximity to certain of the openings 13. Disposed upwardly through certain of these openings 13 are the bolts 23, the angular heads 24, of which, 80 bear against the side faces of the side member 12, of the tie, whereby to prevent rotation thereof. Disposed on the upper face of the member 10, and receiving the bolt therethrough, is a plate 25, the opening 26 85 of which is disposed at such relative distances from the sides of the plate as to provide for properly measuring and spacing the edge of the rail from the appropriate opening 13, in which the bolt 23 is to be disposed, whereby to accommodate rails of 90 different sizes. Thus, with one side of the plate 25 directed toward the rail, one size of rail may be used, while with another side of the plate directed toward the rail, another size of rail may be used, and so on 95 with the other two sides of the plate. Disposed on the bolt, and resting on the plate 25, is a plate 27, which has one end extended and tapered for engagement on the upper face of the base flange of the rail, while the other end of the plate 27 is formed with a 100 depending lug 28 which is disposed down- 105

110

wardly through an adjacent opening 13, said lug, by its engagement with the wall of the opening 13, preventing rotation of the plate on the bolt. A nut 29 is screwed on the 5 upper end of the bolt, and down onto the lock washer plate 30, which has portions 31 bent upwardly against the sides of the nut to prevent rotation thereof, while portions 32 are bent downwardly into engagement 10 with the sides of the plate 27.

There may be two of these fastening means on each side of the rail, or there may be one 15 on each side of the rail, and arranged at opposite sides of the tie, whereby to properly hold the rail from spreading.

What is claimed is:

1. A railway tie comprising an elongated box having its upper wall projecting beyond the sides of the box and provided with fastening receiving openings, a vertical longitudinal central wall in the box having its ends projecting beyond the ends of the box 20

and apertured, and end walls having slots receiving said projecting portions of the central wall and fastening devices disposed through the apertured ends of the central wall.

2. A railway tie comprising an elongated box having its bottom wall projecting beyond the side walls and provided with an opening, said box having a longitudinal central vertical wall the ends of which are intermediately reduced and apertured, and end walls for the box having lugs seated in the openings of the ends of the said bottom and having openings receiving the reduced ends of the said central wall, and fastening means through the said reduced ends.

In testimony whereof, I affix my signature in the presence of two witnesses.

JOHN B. MASERANG.

Witnesses:

E. B. HECKENCHAMP,
GEORGE TIEMEYER.
